DESIGN FOR A HOUSING FOR A SOLENOID OPERATED VALVE

Harvey Graves Chapman, Jr., Glendale, Calif.,
assignor to Adel Precision Products Corp., a cor-
poration of California

Application September 23, 1944, Serial No. 115,424

Term of patent 14 years

(Cl. D78—1)

To all whom it may concern:

Be it known that I, Harvey Graves Chapman, Jr., a citizen of the United States and residing at Glendale, in the county of Los Angeles and State of California, have invented a new, original, and ornamental Design for a Housing for a Solenoid Operated Valve, of which the following is a specification, reference being had to the accompanying drawing, forming part thereof, in which:

Fig. 1 is a view of the housing for the sole-
noid operated valve as seen in front elevation
showing my new design.

Fig. 2 is a plan view thereof.

Fig. 3 is a perspective view thereof.

I claim:

The ornamental design for a housing for a
solenoid operated valve, as shown.
